UNITED STATES PATENT OFFICE.

JOHN L. FLANNERY, OF CHICAGO, ILLINOIS, ASSIGNOR TO THE BOYE NEEDLE COMPANY, OF CHICAGO, ILLINOIS, A CORPORATION OF ILLINOIS.

DISPLAY NEEDLE PACKAGE.

Application filed December 19, 1921. Serial No. 523,439.

To all whom it may concern:

Be it known that I, JOHN L. FLANNERY, a citizen of the United States, residing at Chicago, in the county of Cook and State 5 of Illinois, have invented a new and useful Improvement in Display Needle Packages, of which the following is a specification.

This invention relates particularly to a needle display package; and the primary object is to provide an improved package which can be mounted in a display cabinet of the character shown in my Patent No. 1,361,451, granted December 7, 1920.

The invention enables a needle package of this character to be employed in connection with a display cabinet of special construction. Such cabinets may be furnished by manufacturers of small articles of merchandise to dealers throughout the country; 20 and the chief purpose of the present invention is to furnish a package adapted to such a cabinet, so that sale of the needles can be effected from the cabinet and unauthorized or fraudulent use prevented. Thus, a manufacturer who furnishes the cabinets to dealers gratis, that is to say, with the understanding that the cabinet should be used only in displaying and selling the merchandise of such manufacturer, may supply the 30 improved needle packages herein described which are specially adapted for use in the cabinet, and may guard against unauthorized use of the cabinet.

The invention is illustrated, in its preferred embodiment, in the accompanying drawing, in which

Fig. 1 represents a broken vertical sectional view of a cabinet adapted to receive the improved needle packages; Fig. 2 represents a plan view of one of the needle packages; Fig. 3 represents the improved needle package with the special wrapper employed shown in unfolded condition, a card employed in connection therewith being shown brokenly and disclosing a portion of the ordinary needle package which is, in the practice of the present invention, enfolded in the wrapper shown in Fig. 3; and 50 Fig. 4, an enlarged sectional view of the improved needle package.

In the illustration given, A represents a cabinet of the character shown in the above-mentioned patent, this cabinet being provided with a series of inclined compart-

ments 1, which are bottomless, except that they contain forwardly and upwardly inclined card-supporting strips 1^a; and B, B, needle packages mounted in said compartments.

Each needle package B comprises a special outer wrapper 2; an enclosed card 3 having at one end furcations 3^a which extend thru slits in the wrapper 2; and a needle package 4 which comprises a simple inner wrapper 4^a and the needles 4^b.

The needle packet 4 may comprise simply a narrow strip of paper having its central portion provided in the usual manner with a transverse strip of cloth 4^c thru which the central portions of the needles extend, the end portions of the strip of paper being folded to provide flaps which cover the needles. In Fig. 3, the upper one of these flaps is shown broken away to expose some of the needles.

The outer special wrapper 2 is adapted to fold along transverse lines 2^a and longitudinal lines 2^b. The wrapper 2 is provided at the lower end of the rectangle formed by the crossing of the lines 2^a and 2^b with slits 2^c.

The card 3 is placed on the inner side of the wrapper and has its furcations 3^a extending thru the slits 2^c. The needle packet 4 is inserted back of the card 3. The side flaps of the wrapper 2 are then folded inwardly over the card, and the extremities of the folded wrapper are then folded over the card. The side flaps of the exterior wrapper are designated 2^d and the lower and upper end flaps are designated 2^e and 2^f, respectively.

In practice, it is unnecessary to supply adhesive to hold the end flaps in folded condition, altho such adhesive may be used, if desired.

When the package is completed, the furcations 3^a project from one end of the package, providing between them a space 3^b. This space or slot is adapted to engage the upper edge of the inclined supporting-strip 1^a of the cabinet. Thus, the needle packages may be supported in the rearwardly inclined position shown in Fig. 1. This adapts the needle packages to convenient display in a cabinet. A suitable supply of packages may be stored in the cabinet; and, as sales are effected, the packages may be

taken from the cabinet and delivered to the customer.

The foregoing detailed description has been given for clearness of understanding only, and no unnecessary limitations should be understood therefrom, but the appended claims should be construed as broadly as permissible in view of the prior art.

What I regard as new, and desire to secure by Letters Patent, is—

- 10 1. A needle package comprising a wrapper provided with slits, and a card provided with furcations extending thru said slits, the wrapper being folded about the card.
- 15 2. In a needle package, the combination

of an exterior wrapper provided with slits, a card in said wrapper having furcations extending thru said slits, and a needle packet folded in said wrapper adjacent to said card.

20 3. A needle package comprising an exterior wrapper having folded lateral flaps and having the end portions of the plies folded over the folded flaps, a card enclosed in said wrapper having furcations at one end 25 extending thru slits in the wrapper, and a needle packet within said wrapper and disposed back of said card.

JOHN L. FLANNERY.
